UNITED STATES PATENT OFFICE.

JOZSEPH FARAGO, OF CLARENCE, PENNSYLVANIA.

RAIL-JOINT.

1,140,892.

Specification of Letters Patent.

Patented May 25, 1915.

Application filed February 17, 1915. Serial No. 8,951.

To all whom it may concern:

Be it known that I, JOZSEPH FARAGO, a subject of the King of Hungary, residing at Clarence, in the county of Center and State 5 of Pennsylvania, have invented certain new and useful Improvements in Rail-Joints, of which the following is a specification.

This invention relates to certain new and useful improvements in rail joints.

10 An object of the present invention is to provide a rail joint of the scarf type in which the tread portions alone of meeting rail ends are constructed to provide an interlocking connection and to have associated 15 with this joint coöperating fish plates to provide a lock.

A further object of the invention is to provide a rail joint in which the tread portions are formed of interlocking sections and in 20 which coöperating fish plates engage the rail webs and carry integrally formed locking members constituting effective means for holding the rail ends locked.

With the above general objects in view 25 and others that will appear as the nature of the invention is better understood, the same consists in the novel construction, combination and arrangement of parts to be herein-after more fully described and then claimed.

30 In the accompanying drawings which show the preferred embodiment of the present invention and to which reference is had herein by like characters designating corresponding parts throughout the several views:—

Figure 1 is a side elevational view of two meeting rail ends constructed in accordance with the present invention. Fig. 2 is a top plan view of the same, partly shown in section, to illustrate the fish plate lock. Fig. 3 is a perspective view of one of the rail ends. Fig. 4 is an inverted perspective view of the other rail end. Fig. 5 is a perspective view of a portion of one of the fish plates illustrating the key slot formed therein, and, 45 Fig. 6 is a detail perspective view of a portion of the other fish plate illustrating the integral locking bolt carried thereby.

Referring more in detail to the accompanying drawings, the reference numeral 10 designates rail supporting ties of suitable construction and 11 designates fastening spikes also of the usual form.

Supported on the ties 10 are the rails 12 and 13, more clearly shown in Figs. 3 and 4. The rail end 12 includes the web portion 12^a

and tread portion 12^b. As illustrated, the tread portion 12^b is cut-away to provide a seat portion 12^c which is substantially half the height of the tread portion, while the 60 end of the seat 12^c is further angularly cut as at 12^d coöperating with the other rail end. A recess 12^e is provided in the seat 12^c and is preferably angular in plan view.

The rail end 13 is adapted to coöperate 65 with the rail end 12 and includes the web portion 13^a, and the tread portion 13^b. The tread portion is cut-away to provide an overhanging ledge 13^c which is substantially half the thickness of the height of the head 70 portion while the rear end thereof is further cut to provide an angle shoulder 13^d. A projecting lug 13^e, preferably angular in cross-section depends from the ledge 13^c and is adapted for seating in the recess or 75 socket 12^e.

In assembled position, the ledge 13^c of the rail 13 rests upon the seat 12^c of the rail 12, with the angle shoulder 13^d received in the 80 cut-away portion 12^d to prevent further movement of the rail ends toward each other and thereby obviate danger of the depending lug 13^e being sheared off while the lug 13^e is received within the socket 12^e. In this position, a portion of one rail tread overlaps 85 a portion of the other rail tread, and with the webs and base flanges contacting.

In order to hold the rails 12 and 13 in such position, I have provided the fish plates, shown in detail, in Figs. 5 and 6, and 90 designated 14 and 15. The fish plate 14 has preferably formed integral therewith locking bolts 14^a carrying enlarged heads 14^b on the outer ends thereof, while the fish plate 15 is provided with a pair of key-hole shaped 95 openings 15^a adapted for the reception of the bolts 14^a as shown in Fig. 2, and to be moved so that the bolt 14^a rests in the narrow portion of the opening and in which position the head 14^b will prevent its removal. The rail webs 12^a and 13^a are provided with openings 16 to permit the bolts 14^a to pass therethrough and to be in the position as clearly shown in Figs. 1 and 2, and at which time the fastening spikes 11, 105 passing through suitably positioned edge recesses formed in the base flanges of the fish plates 14 and 15, enter the ties 10 to securely lock the rail ends thereon.

While I have shown and described the 110 preferred embodiment of the present invention, I do not wish to confine myself to the

exact details of construction shown, as various forms, modifications and arrangements of the parts as shown may be had without departing from the spirit and scope of the invention as claimed.

What I claim as new is:—

A rail joint including meeting rail ends, one of the rail ends having the tread portion thereof cut-away to provide a seat, the 10 end of the seat being further cut-away to provide an angular recess formed wholly within the tread adjacent the end thereof, a centrally disposed socket provided in the seat portion, the other rail end having a 15 projecting tread portion cut-away to pro-

vide an overhanging ledge, the rear end of the ledge being further cut to provide an angular shoulder, a centrally disposed depending lug carried by the ledge and spaced from the edges thereof, said lug and shoulder adapted to be received in the seat and angular recess in the seat portion, and fish plate locking means associated with the rail ends.

In testimony whereof I affix my signature 25
in presence of two witnesses.

JOZSEPH FARAGÓ.
